UNITED STATES PATENT OFFICE.

CARMELO FRENI, OF WATERBURY, CONNECTICUT.

SURFACING TOOL.

Application filed October 1, 1926. Serial No. 138,974.

This invention relates to a surfacing tool, and it is the principal object thereof to provide a simple and effective mechanism that may be used by a plasterer for smoothing off 5 the surface of a coat of plaster or the like.

The details and arrangement of parts of my new and improved tool will be apparent from an inspection of the drawings in connection with the description hereinafter contained, and wherein a preferred embodiment 10 of the invention is disclosed for the purpose of imparting a full understanding of the same.

In the drawings, wherein like numerals of 15 reference designate like parts in the several figures;

Figure 1 is a fragmentary side elevation of my improved surfacing tool;

Figure 2 is a view of the underside there- 20 of;

Figure 3 is an end elevation; and

Figure 4 is a fragmentary detail view of a portion of one of the surfacing strips.

In the embodiment of my invention as 25 shown herein, 10 designates the base member, shown herein as substantially rectangular in shape, although not limited thereto, the ends of which are turned outwardly to form the surfacing strips 11—11. While I have only 30 shown these strips along two of the edges of the base member, all or part of the remaining edges may be so formed if desired.

Fixed to the back of the base member 10 are the standards 18, to which the handle 19 35 is secured by the stud 20.

Secured to the under face of the base member are a plurality of surfacing strips 12, 13, 40 14 and 15, which are all of substantially the same height as the surfacing strips 11. These latter strips are preferably formed of right angle plates 16 that are secured by the rivets 17 or the like. As arranged, the strip 12 is substantially parallel with the strips 11 and each of the strips 13 are at an angle to the 45 adjacent strips 14 and 15.

I find it convenient to arrange these strips as shown, so that over the surface to be smoothed there are surfacing strips in contact therewith that scrape the surface in a

path at right angles to the length of the tool 50 and other strips that are at an angle thereto and at substantially a right angle to each other. By this means, the tool as it moves over the face will remove all projecting portions by a scraping action with some of the strips and a shearing action by other strips, this shearing action being in several directions.

In use, the operator grasps the handle 19 and moves the tool with the outer edges of the surfacing strips in contact with and in all 60 directions over the surface to be smoothed. During this motion some of the strips push the excess material in front of it while other of the strips cause such material to move along the face of the surface by reason of 65 their shearing action. The result is, that all of the rough spots are either cut or smoothed off, producing a very smooth and even finish.

Having described my invention, what I 70 claim as new and desire to secure by Letters Patent, is:

1. A tool of the character described, having a plurality of surfacing edges, which are arranged so that some are parallel with each other and others at an angle thereto and intersecting each other, at a point between the sides of the tool, whereby a plurality of angular pockets are formed around the center of such intersections in which excess material may accumulate and furnish a supply to 80 fill depressions in the surface operated on.

2. A tool of the character described, having a plurality of surfacing edges arranged so that some are parallel with each other and others at an angle thereto and intersecting each other, at a point between the sides of the tool, whereby a plurality of angular pockets are formed around the center of such intersections in which excess material may accumulate and furnish a supply to fill 85 depressions in the surface operated on, said edges being preferably formed from independent members and rigidly secured relatively to each other.

3. A tool of the character described, having a base member formed with two outwardly turned edges and a plurality of surfacing strips secured thereto, between such edges,

the outer faces of the strips and edges forming straight surfacing faces, some of the strips being parallel with other strips and intersecting each other at a point between the 5 sides of the base member, whereby a plurality of angular pockets are formed around the center of such intersections in which excess

material may accumulate and furnish a supply to fill depressions in the surface operated on.

10

In testimony whereof, I have hereunto affixed my signature.

CARMELO FRENI.
